[57] CLAIM

The ornamental design for a leaf mulching attachment for rotating line trimmer, as shown and described.

DESCRIPTION

FIG. 1 is a top plan view of a leaf mulching attachment for rotating line trimmer, showing my new design; FIG. 2 is a front elevational view thereof, the rear being a mirror image;

FIG. 3 is a bottom plan view thereof;

FIG. 4 is a right side elevational view thereof, the left side being identical.

*FIG. 1**FIG. 2**FIG. 3**FIG. 4*
